Primary Examiner — Selina Sikder*(74) Attorney, Agent, or Firm* — Harness, Dickey & Pierce, P.L.C.(57) **CLAIM**

The ornamental design for a box cover for limit switch, as shown and described.

DESCRIPTION

FIG. 1 is a perspective view of a box cover for limit switch showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines depict environmental subject matter only and form no part of the claimed design. The oblique short lines in FIGS. 1 and 2 views are intended to illustrate that the surface is translucent.
